US0D1112832S

(12) **United States Design Patent** (10) **Patent No.:** **US D1,112,832 S**
(45) **Date of Patent:** **** Feb. 10, 2026**

(54) **FRAME MEMBER**

(71) Applicant: **EARTHECO GLOBAL PTY LTD**,
Brendale (AU)

(72) Inventors: **Jarad Wilson**, Brendale (AU); **Wade Price**, Brendale (AU)

(73) Assignee: **EARTHECO GLOBAL PTY LTD**,
Brendale (AU)

(**) Term: **15 Years**

(21) Appl. No.: **29/875,954**

(22) Filed: **May 12, 2023**

(30) **Foreign Application Priority Data**

Nov. 16, 2022 (AU) 202216739

(51) **LOC (15) Cl.** **25-01**

(52) **U.S. Cl.**
USPC **D25/126**

Wyatt, P.C.

(57) **CLAIM**

The ornamental design for a frame member as shown and
described.

DESCRIPTION

FIG. 1 is a perspective view of a frame member, showing our
new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is an enlarged view of FIG. 4;

FIG. 9 is an enlarged view of the area indicated in FIG. 2;
and,

FIG. 10 is an enlarged view of the area indicated in FIG. 8.
The broken lines shown in FIGS. 8-10 illustrate areas that
are showing enlarged portions of the frame member and
form no part of the claimed design.

1 Claim, 4 Drawing Sheets
